CLAIM

The ornamental design for a combined step and hand hold for use on a helicopter, substantially as shown and described.

DESCRIPTION

FIG. 1 is a perspective view of a combined step and hand hold for use on a helicopter, showing my new design;

FIG. 2 is a front view thereof;

FIG. 3 is a side view thereof;

FIG. 4 is a rear view thereof;

FIG. 5 is a top view thereof; and

FIG. 6 is a bottom plan view thereof.
